UNITED STATES PATENT OFFICE.

THOMAS S. BAYLES, OF TORONTO, ONTARIO, CANADA, ASSIGNOR OF TWO-THIRDS TO THOMAS R. WOOD AND ANDREW J. SOMERVILLE, BOTH OF SAME PLACE.

WIRE-SPOOLING MACHINE.

SPECIFICATION forming part of Letters Patent No. 293,842, dated February 19, 1884.

Application filed May 24, 1883. (No model.)

To all whom it may concern:

Be it known that I, THOMAS STUBBS BAYLES, of the city of Toronto, in the county of York, in the Province of Ontario, Canada, machinist, have invented certain new and useful improvements in a machine for guiding the wire onto the spool upon which it is being wound off the coil, of which the following is a specification.

10 The object of the invention is to dispense with the manual labor employed in guiding the wire from the coil onto the spool upon which it is being wound; and it consists, essentially, of a grooved pulley suitably supported and operated by mechanism arranged to impart a reciprocating movement to the said pulley in such a manner that the wire passing around it shall be guided in regular convolutions from end to end of the spool, as herein-
15 after more particularly explained.

Figure 1 is a perspective view of the machine. Fig. 2 is an enlarged detail of the spindle F, showing the right and left hand screws a b. Fig. 3 is an enlarged detail, showing the shape of the pin H. Fig. 4 is an enlarged detail, showing the shape of the inside of the cap to the bearing G'.

A is the coil of wire, carried on a suitable reel, and, after passing around the pulley B, 30 is connected to the spool C. The pulley B is grooved, so as to retain the wire passing around it, and is journaled on a bar, D. This bar is pivoted at D', and is forked at its other end, E, so as to fit into a groove made in the 35 end of the spindle F. This spindle F is carried in suitable bearings, G G', and is parallel, so that it will move longitudinally in the said bearings. A coarse-pitched right-hand thread, a, is cut on the spindle F through the bearing 40 G', and a left-hand thread of the same pitch is also cut at the same point, so that the ends of the left-hand thread shall intersect with the ends of the right-hand thread.

H is a pin passing through one of the bearings G', and extends into the thread cut, as described, on the spindle. Owing to the fact that the right-hand and left-hand threads a and b are cut so that their ends shall intersect with each other, the pin H, which is fixed and 50 extends into the thread, prevents any longitudinal movement in the spindle when stationary; but when the spindle is caused to re-

volve, a reciprocating longitudinal movement is imparted to the spindle F by the right and left hand thread acting against the pin H.

55 I is a guide extending from the frame J of the machine.

K is a friction-roller journaled in a bracket fixed to the pivoted bar D. This guide I constitutes a solid resistance to the pull of the 60 wire being wound on the spool C, while the roller K prevents any undue friction which might be caused by the said strain.

When about to wind the wire from the coil A onto the spool C, the wire is passed once 65 around the pulley B, and then connected to the spool C. The spool is then caused to revolve, and, corresponding with that action, a similar movement is imparted to the spindle F. Then, owing to the action of the pin H in the grooves a and b, a longitudinal reciprocating movement is imparted to the spindle, the revolving and reciprocating movement of the spindle being timed, so as to wind the wire A' in regular convolutions around the spool C. 70

75 On reference to Fig. 3 it will be seen that the pin H has a crescent-shaped end, H', and formed to fit into the thread a b, thus giving a good bearing to the pin H in the said thread. As the angle of this crescent H' will be altered 80 each time that it changes from the right to the left hand thread, provision is to be made to permit of this adjustment without permitting the pin H to revolve altogether. To permit this adjustment, I form a groove, h, in the cap 85 of the bearing G', as shown in Fig. 4, a little wider than the crescent H', which fits into the groove h.

What I claim as my invention is—

1. In a wire-spooling machine, the combination, with a wire-guide and a spindle carried in suitable bearings constructed to give motion to said wire-guide, and having a right and left hand thread cut on it, so that the end of one thread shall intersect with the other, of a pin, H, fixed in the spindle-bearings fitting into the threads, so that the spindle, when revolving, shall have a reciprocating longitudinal movement imparted to it and impart the same to the wire-guide, substantially as and 95 for the purpose specified.

2. In a wire-spooling machine, the combination of a guiding-pulley, B, interposed between the coil and spool, and mechanism ar-

ranged to impart a reciprocating movement to the said pulley in such a manner that the wire passing around it shall be guided onto the spool in regular convolutions, substantially as and for the purpose specified.

3. In a wire-spooling machine, a pulley, B, grooved to receive the wire being guided, and journaled on a spindle fixed to the pivoted bar D, in combination with mechanism arranged to rock the said bar for the purpose of guiding the wire in regular convolutions onto a revolving spool, substantially as and for the purpose specified.

4. In a wire-spooling machine, a pulley, B, journaled on the pivoted bar D, and grooved to receive the wire as it passes from the coil

A to the spool C, in combination with the pin H, fixed in the spindle-bearing, and the revolving spindle F, having a right-hand thread, *a*, cut on it, and intersecting with the left-hand thread *b*, so that the end of the pin H, fitting into the threads, will impart a reciprocating longitudinal movement to the revolving spindle, substantially as and for the purpose specified.

Dated at Toronto, this 4th day of May, A. D. 1883.

THOS. S. BAYLES.

In presence of—

CHAS. C. BALDWIN,
F. BARNARD FETHERSTON H.
